UNITED STATES PATENT OFFICE.

WILLIAM GOYDER AND NORMAN GILES BECKWITH, OF LONDON, ENGLAND.

HYDRAULIC PRESS.

1,054,197.

Specification of Letters Patent.

Patented Feb. 25, 1913.

Application filed October 8, 1910. Serial No. 586,027.

To all whom it may concern:

Be it known that we, WILLIAM GOYDER and NORMAN GILES BECKWITH, both subjects of the King of Great Britain, residing at 5 London, England, have invented new and useful Improvements in Hydraulic Presses, of which the following is a specification.

This invention relates to pistonless hydraulic presses of the type in which a moving pressure plate is carried by a collapsible wall between guides which support a fixed pressure plate.

According to this invention, the collapsible wall is formed of a plurality of steel 10 cylinders connected together by suitable flexible material.

The accompanying drawing shows one form of press made in accordance with this invention.

20 Figure 1 is an elevation; Fig. 2 a horizontal section on line X—X of Fig. 1; and Fig. 3 a vertical section on line Y—Y of Fig. 2. *a* are the guides carrying the fixed plate *b*. *c* are short steel cylinders the uppermost 25 of which carries the movable pressure plate *d*, while the lowermost is secured to the bed plate *e*. The cylinders *c* are connected to one another by flexible material *f* in the internal undulations of which they are entirely embedded as shown in Fig. 2. The 30 top cylinder and preferably also all the other cylinders *c* carry rings *g* sliding on the guides *a*. Or instead of the sliding rings *g*, the plates *e* and *d* respectively may carry 35 guiding rods *g*, *g* which will serve not only to maintain the cylinders *c* always in a concentric condition, whether the chamber is expanded or collapsed, but will also serve to limit the downward movement of 40 the plate *d* and cylinders *c*, and prevent undue pressure or weight being put upon the corrugations of the flexible material when the press is out of use. That is to say, when 45 the press is out of use or at rest as in Fig. 1, the weight of the movable pressure plate

will be carried by the bed-plate *e* by reason of the lower ends of the rods *g* coming into contact with the bed-plate *e*, and the upper ends of the rods *g* coming into contact with the movable pressure plate *d*. 50

Such a press is cheaply and easily made, is steady, and very strong.

Having described the invention, what we claim as new and desire to secure by Letters Patent is:

1. A pistonless hydraulic press comprising a moving pressure plate supported by a collapsible wall composed of a plurality of superposed metal cylinders spaced apart from one another but connected together 60 and to the moving pressure plate and bed-plate by flexible material, whereby the flexible material between the ends of the metal cylinders permits of the expansion and collapsing of the press, the metal cylinders 65 being entirely embedded within the inner undulations of the flexible material, substantially as described.

2. A pistonless hydraulic press comprising a moving pressure plate supported by a 70 collapsible wall composed of a plurality of superposed metal cylinders spaced apart from one another but connected together and to the moving pressure plate and bed-plate by flexible material, whereby the flexible 75 material between the ends of the metal cylinders permits of the expansion and collapsing of the press, the metal cylinders being entirely embedded within the inner undulations of the flexible material, and in- 80 internal guiding and stop rods, substantially as described.

In testimony whereof we have signed our names to this specification in the presence of two subscribing witnesses.

WILLIAM GOYDER.
NORMAN GILES BECKWITH.
